W. H. LEONARD.

ROCK DRILL.

APPLICATION FILED MAY 1, 1914.

1,251,391

Patented Dec. 25, 1917.

UNITED STATES PATENT OFFICE.

WILLIAM H. LEONARD, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,251,391.

Specification of Letters Patent. Patented Dec. 25, 1917.

Application filed May 1, 1914. Serial No. 835,632.

To all whom it may concern:

Be it known that I, WILLIAM H. LEONARD, a citizen of the United States, residing at Denver, in the county of Denver and State of Colorado, have invented new and useful Improvements in Rock-Drills, of which the following is a specification.

The present invention relates to means for delivering cleansing fluid to the drill holes made by rock drilling machines, and in its specific sense, is part of the mechanism of a hammer drill.

The object is to provide novel and simple mechanism for insuring the discharge of a liquid cleansing agent into the bore of a drill bit and its conduction by said drill bit to the bottom of the drill hole, at the same time utilizing gaseous fluid, not only for the purpose of assisting in the cleansing action, but for directing the liquid into the drill bit and preventing its entrance into, and possibly flooding the motor.

A simple embodiment of the invention is illustrated in the accompanying drawings, wherein:

Figure 1 is a view in elevation and somewhat diagrammatic in its character of a hammer drill, with portions broken away and the novel structure illustrated in section.

Fig. 2 is a detail cross sectional view through the tubes or conduits on the line 2—2 of Fig. 1.

Similar reference numerals designate corresponding parts in all the figures of the drawings.

In the embodiment illustrated, the motor of the drill, as usual, consists of a cylinder member 3 having a front head 4 and a rear head, which in the embodiment illustrated, consists of sections 5 and 6. In the cylinder member operates a reciprocating hammer piston 7, which on its working stroke, strikes a tappet 8 located in the front end of the cylinder member 3, said tappet being interposed between the piston 7 and the rear end of the removable drill bit 8a. This drill bit, as usual, is provided with a longitudinal bore 9 opening through both ends. The operation of the piston 7 is controlled by an automatic distributing valve located in a valve chest 9a. As these are well known features, it is believed to be unnecessary to further describe the same. Furthermore, it will be evident that they may be modified in various ways.

The tappet 8 is provided with an axial bore 10, the front end of which is slightly reduced, as illustrated at 11, and is in register with the bore 9 of the drill bit. The section 5 of the rear cylinder head is in the form of a plate having a central enlargement 12, which is provided with a pocket 13 opening through the rear face of the same, said pocket being centrally disposed. A tube 14 has its rear end located in the pocket, and said tube extends forwardly through the piston 7 and into the bore 10 of the tappet, terminating short of the reduced portion 11 of said bore. The rear end of the tube is surrounded by a packing 15, preferably of rubber, which is crowded against said tube by means of a gland 16 slidably mounted in the rear end of the pocket 13. Gaseous fluid, under pressure, is supplied to the rear end of the tube 14 through a passageway 17 leading from the valve chest 9a, said passageway being formed in the section 5 and in the gland 16, the passageway communicating with the rear end of the tube. Thus, the said fluid will discharge into the bore 10 of the tappet 8, and through said bore, into the bore 9 of the drill bit.

Another and smaller tube 18 is disposed longitudinally within the tube 14 in spaced relation to the walls thereof. This tube has its rear end extending through the gland 16, and into a pocket 19 formed in the outer section 6 of the rear cylinder head. Packing 20, in the form of rubber, is interposed between the rear wall of the pocket 19 and the gland 16. Thus, said packing is crowded against and around the rear end of the tube 18 to prevent leakage and also to hold said tube in place. It will thus be seen that by clamping the head sections 6 and 5 together, which is ordinarily done by the side bolts of the motor (not shown), the rear end of the tubes will be effectively secured in place. The section 6 of the rear cylinder head is provided with an internally threaded socket 21 to receive a hose coupling, by which liquid can be supplied to the motor from any suitable source, and this socket 21 has communication with the rear end of the tube 18, through a port 22. The front end of the tube 18 projects beyond the front end of the tube 14, into the reduced portion 11 of the bore of the tappet, said front end being preferably tapered, and being spaced from the walls of the bore 10—11, the tube 18, how-

ever, terminating short of the drill bit 8^a. In order to maintain the front end of said tube 18 in its axial relation, one of said tubes, for example, the outer one, is provided with 5 offset spaced lugs 23, which engage the tube 18 and center the same.

Briefly described, the operation of the device is substantially as follows:—When the motor is in operation, with a drill bit therein, 10 air or other gaseous fluid flows from the valve chest 9^a through the passageway 17, into the outer tube 14 and discharges from the front end of said tube around the tube 18. It is delivered from the tappet into the 15 bore of the drill bit, and traversing said drill bit, discharges from the front end of the same into the bottom of the drill hole, blowing out the cuttings. Whenever water or liquid is admitted through the nipple 21 20 and passageway 22 into the rear end of the tube 18, said liquid will pass through the tube and be discharged from its front end into the rear end of the drill bit. When so discharged, it is surrounded by the tubular 25 column of air, discharging from the front end of the tube 14, and this confines the stream of liquid, insuring that it will cross the joint between the tappet and the drill bit and discharge into the bore of said drill 30 bit. There is therefore practically no leakage of the liquid into the machine.

The termination of the tube short of the drill bit 8^a is important for the reason that when the tube is extended into the drill bit, 35 it is apt to be cut off by burs formed upon the rear end of the bit, due to the continued hammering action thereagainst. If, however, the tube is thus terminated there is danger of leakage around the joint behind 40 the drill bit. The tubular column of air, as above described, confines the stream of liquid as it crosses the joint, and it is therefore important that this tubular air column be maintained. For these reasons, the utilization 45 of means such as the parts 23 for maintaining the inner tubes centered with respect to the outer tube is important, for if the tube is supported merely at its rear end, its front end is apt to become displaced from 50 the desired axial disposition, it being remembered that the tool is subjected to continuous shocks and vibrations incident to the operation thereof. The present centering means therefore is important in connection 55 with the disposition of the discharge ends of the tubes.

From the foregoing, it is thought that the construction, operation and many advantages of the herein described invention will be apparent to those skilled in the art, without further description, and it will be understood that various changes in the size, shape, proportion, and minor details of construction may be resorted to without departing from 60 the spirit or sacrificing any of the advantages 65

of the invention. For example, other means may be employed for securing the rear ends of the tubes, and a different connection for the water supply may be employed.

Having thus fully described my invention, 70 what I claim as new, and desire to secure by Letters Patent, is:—

1. In apparatus of the character set forth, the combination with a piston for operating on a drill bit, of means passing through 75 the piston for introducing a liquid cleansing agent into the drill bit operated on by the piston, means adjacent to such drill bit for supporting said introducing means against lateral displacement with respect to the drill 80 bit, means also passing through the piston and terminating short of the drill bit for introducing a gaseous cleansing agent into the drill bit, and means adjacent to such drill bit for maintaining said latter means 85 against lateral displacement.

2. In apparatus of the character set forth, the combination with a piston for operating on a drill bit, of a plurality of conduits extending through the piston for delivering 90 to the bore of said drill bit, means for supplying a liquid cleansing agent to one conduit and a gaseous cleansing agent to the other conduit, the conduit for the gaseous cleansing agent having its discharge end 95 terminating short of the drill bit, and means adjacent the discharge ends of said conduits for preventing the lateral displacement of both with respect to the drill bit operated upon.

3. In apparatus of the character set forth, the combination with a piston for operating on a drill bit, of a plurality of conduits located one within the other, the outer conduit having its discharge end terminating 105 short of such drill bit, said conduits extending through the piston for delivering to the bore of the drill bit operated on, means for supplying a liquid cleansing agent to one conduit and a gaseous cleansing agent to 110 the other conduit, means for supporting the discharge end of the outer conduit against lateral displacement with respect to the drill bit, and means interposed between the conduits for holding them in spaced relation 115 and preventing the lateral displacement of the inner conduit.

4. In apparatus of the character set forth, the combination with a reciprocating piston for operating on a drill bit, of axially disposed conduits extending axially through the piston and discharging into the bore of the drill bit operated upon, means for supplying a liquid cleansing agent to the inner conduit, and a gaseous cleansing agent to 125 the outer conduit, said outer conduit having its discharge end terminating short of the drill bit, means for supporting the discharge end of the outer conduit against lateral displacement with respect to the bore of the 130

drill bit operated upon, and means interposed between the free end portions of the conduits for maintaining them in spaced relation and thereby securing the inner conduit against lateral displacement with respect to the outer conduit and the bore of the drill bit operated upon.

5. In apparatus of the character set forth, the combination with a drill bit having a bore, of a reciprocating piston for operating on the drill bit, a cylinder member containing the piston and having a rear head, cleansing fluid conducting tubes extending from the rear head through the piston and delivering to the drill bit, a packing member for each tube in the rear head, and a movable gland interposed between the packing members.

6. In apparatus of the character set forth, the combination with a drill bit having a

bore, of a reciprocating piston for operating on the drill bit, a cylinder member containing the piston and having a rear head, axially disposed conduits extending from the rear head through the piston and delivering 25 to the bore of the drill bit, said conduits extending different distances into the rear head, packings surrounding each of the rear ends of the conduits, a packing gland interposed between the packings, and means for 30 supplying cleansing fluid to the rear ends of the conduits, one of the supplying means including a port located in the gland.

In testimony whereof I have hereunto set my hand in presence of two subscribing witnesses.

WILLIAM H. LEONARD.
